Application May 13, 1943, Serial No. 486,814

7 Claims. (Cl. 261—118)

The present invention relates to spray booths and particularly to the wash type of spray booth.

In spray booths of this type the spray laden air usually flows from the work locus downwardly and rearwardly in the work chamber and over a water receptacle at the rear lower portion of the booth and beneath the lower end of the water curtain apron where a water curtain flows downwardly in a sheet to wash out suspended particles from the air as it flows rearwardly over the water receptacle and through the water curtain flowing down from the lower end of the apron into the receptacle. The air then usually flows through a washing chamber at the rear of the apron for further washing out of suspended material. Examples of such structures are disclosed in the Gustafsson Patent No. 2,180,586, granted November 21, 1939, the Roche, Jr., et al. Patent No. 2,227,465, granted January 7, 1941, and the Roche, Jr., et al. Patent No. 2,266,335, granted December 16, 1941.

Among the objects of the invention is to provide a novel means for causing an upward flow of the spray laden air through one or more sheets of washing liquid which may be horizontally projected or upwardly projected or both to wash out the greater part of the suspended matter in the upwardly flowing air, and at the same time causing a downwardly flowing sheet or curtain of water over an apron extending down into and below the normal level of the water in the receptacle in the lower rear portion of the booth whereby the washed out material is caused to be deposited onto or into the water in the forward portion of the receptacle and in front of the apron. By reason of the apron extending down into the water in the water receptacle, passage of air to the rear of the apron is prevented at the lower end of this apron. Any sprayed particles hurled or projected toward the apron will be carried down by the sheet or curtain of water flowing down over the face of the apron and into the forward portion of the receptacle.

The invention also comprehends the further upward flow of the air through a second more or less horizontally projected sheet of water for further washing of the air, this second sheet being so projected against a forward part of the booth, as a rearwardly extending wall forwardly spaced from the upper portion of the apron, as to distribute the water on said wall and form the above first mentioned more or less horizontally projected sheet of water for first washing the upward flowing air, and to form a water curtain or sheet on the face of the apron.

Further, the invention also provides for a further sheet of water, which may be in one form of device a third sheet, which is projected more or less horizontally and toward a second apron located spacedly rearwardly of the previously mentioned apron to form a sheet or curtain flowing downwardly over the forward face of the second apron and to pour from the lower end of the second apron down into the receptacle. The lower end of the second apron is spacedly above the water in the receptacle to provide a passage for the air to a washing chamber at the rear of the second apron. The air passes downwardly through said further sheet of water into the chamber provided between the first and second aprons thus receiving its further washing in said further sheet. Then the air passes through a still further sheet of water, which may be in one form of device, a fourth sheet or curtain of water flowing downwardly from the lower end of the second apron in the passage beneath said lower end of the second apron, thus receiving its further, such as a fourth, washing. Then the air flows upwardly in a wash chamber between said second apron and the rear wall of the device where the air receives the final, such as a fifth, washing as it passes through more or less horizontally projected sheets of water in said washing chamber.

The invention may also comprehend means for increasing the number of washings of the traveling stream of air to more efficiently remove the residual particles or the like of suspended material, depending upon the kind of material being suspended, some being more difficult of removal than others. As for instance, as the air stream passes upwardly from in front of the first apron and then reversely to and into the space rearwardly of the first apron and between said first apron and the second apron, the means for projecting the washing liquid, such as water, may cast or project a plurality of sheets of water transversely of said stream of air, such as forwardly, upwardly and rearwardly.

Also, for the purpose of preventing the adhering of residual and suspended particles of material carried by the air stream, as it changes its course from in front of the front apron to in front of the rear apron, to the wall over or about said stream, means may also be provided for projecting, as from the already mentioned water sheet projecting means or from additional sheet projecting means, sheets of water over and along the surface of such wall, the water of such latter water sheets resultantly uniting with the

water sheets flowing down over the surfaces of the aprons; both the forward and rear aprons.

As a further feature which the novel device may comprehend is the provision of means in the washing chamber at the rear of the second or rear apron for effecting a multiple washing of the rising stream of air; such means comprehending the projecting or casting, more or less horizontally, of a plurality of vertically spaced sheets of water.

Other objects, advantages, capabilities, features, process steps and the like are comprehended by the invention as will later appear and as are inherently possessed by the invention.

Referring to the drawings:

Fig. 1 is a vertical transverse sectional view of a spray booth constructed in accordance with the invention;

Fig. 2 is a transverse sectional view on an enlarged scale of the water sheet forming means;

Fig. 3 is a fragmentary perspective view of the water sheet forming means;

Figs. 4, 5, 6 and 7 are fragmentary sectional views of different or alternative forms of water projecting, washing, and curtain forming means; and,

Fig. 8 is a fragmentary sectional view of an alternative form of washing means for multiple washing.

Referring more in detail to the drawings, the embodiment selected to illustrate the invention is shown with the booth having a rear wall 1, a top 2, end or side walls 3, a front wall 4, and a water receptacle 5 located at the rear lower portion of the booth and extending between the end walls 3. On the top 2 is an exhaust chamber 6 on which is mounted a motor 7 operatively connected by a belt 8 to a fan 9, the belt 8 passing through a belt casing 10. The exhausted air passes out up through an outlet 11.

Intermediately of the rear wall 1 and the forward wall 4 is provided an upright and preferably inclined wall or apron 12 having its lower end 13 spaced above the water 14 in the receptacle 5 to provide a passage 15 below the lower end 13 of said apron 12 and above the water 14. The upper end of the apron 12 has an extension 16 which curves upwardly and forwardly to join the front wall 4. The apron 12 and its extension 16 extend to the end walls 3.

Between the rear wall 1 and the apron 12 is provided a washing chamber 17 in the upper portion of which is located a suitable water eliminator 18, and above the eliminator 18 and between the rear wall 1 and the extension 16 is provided a discharge chamber 19 having a discharge port 20 opposite the fan 9. This chamber is of larger cross sectional area at the top than the chamber 17 to afford the use of a large capacity fan and to lower the velocity of flow of air prior to its engagement by the fan blades.

Spaced forwardly of the apron 12 is provided another wall or apron 21 extending between the walls 3 and preferably held in inclined position as shown by any suitable means such as bars (not shown) connected to the walls 3 and the apron 21. The apron 21 is composed of segments 22, 23 and 24 removably connected together by suitable joint means 25 and 25a. Each joint comprises an upper flange 26 of a lower segment slidably fitting into a channel 27 at the lower end of an upper segment, as shown in Fig. 1. When it is desired to remove or replace a segment it is only necessary to move the segment whereby the flange 26 slides out of or into

the channel 27. The upper segment 24 is fastened to the lower side of a water distributing duct 28 in any suitable manner.

The front wall 4 has a depending rearwardly inclined wall portion or apron 29 extending between the walls 3 and having its lower edge 30 spaced forwardly of the upper portion of the apron 21 to provide an elongated opening or port 31 between said lower edge 30 and said upper portion of the apron 21, through which opening 31 the air passes upwardly into the chamber 32 provided within the walls 4 and 16 (see Fig. 1) and across which opening a sheet of water is projected to the upper end portion of the apron 21 to wash said air and to separate out particles of material carried by the air.

Between the aprons 21 and 12 is provided a chamber 33 which is wider at its base than at its upper end, that is, where it joins the chamber 32.

A distributing duct 28a is also provided in the chamber 17 and both ducts 28 and 28a extend through the side or end walls 3 and are connected in a circulating system having a suitable pump (not shown), the pump having its intake 25 (not shown) connecting at a low point with the rear portion of the receptacle 5.

Both distributing means shown in Fig. 1 are alike and are shown more in detail in Figs. 2 and 3. Each distributing means comprises a duct 28 or 28a having spaced above the duct an elongated distributing plate 34 extending between the walls 3 and being arc shaped or curved in cross section with the concave side opposite the top portion of the duct. The top portion of the duct has a series 30 of discharge orifices 35 through which the water is projected upwardly against the concave or lower side of the plate 34. By so curving the plate 34 the water is componently forced to move more or less longitudinally of the plate, and at various 35 angles, and also transversely so that a continuous and substantially uniform sheet of water will be projected from each edge 36 and 37 of the plate 34 and for the whole length of the plate.

Hence, in chamber 32 is projected a forwardly 45 directed sheet 38 of water to impinge on the wall 29, and a rearwardly directed sheet 39 of water to impinge on the apron 12, and in the chamber 17 is projected a forwardly directed sheet 40 of water to impinge on the rear face of the apron 12, and 50 a rearwardly directed sheet of water 41 to impinge on the forward face of the rear wall 1.

The sheet 38 of water impinging on the wall 29 is distributed on said wall 29 to form a sheet 42 of water which is projected across the opening 55 31 to impinge on the apron 21 and thence to flow down as a curtain or sheet 43 of water on the forward face of the apron 21 and thence into the forward portion 44 of the receptacle 5 where the washed down material floats on or remains in the 60 water in the forward portion 44 of the receptacle 5.

The sheet 39 of water impinging the upper portion of the apron 12 flows down as a curtain or sheet 45 over the forward face of the apron 12 65 and falls down as a curtain or sheet from the lower end of the apron 12 through the opening 15 and into the rear portion of the receptacle 5. At the same time due to the turbulence created by the flow of air and the projection of the water sheets water also moves in a sheet or curtain down along the rear face of the apron 21 to maintain it constantly wet and to carry down any particles of material that might have moved in that direction. Likewise the sheet 40 of water from 70 the distributor 28a impinging on the rear face 75

of the wall or apron 12 forms a sheet or curtain 47 which flows down to the end 13 and through the opening 15, uniting with the curtain flowing down from the front of the apron 12 as described above. Also the sheet 41 impinges the rear wall 1 and flows down as a curtain or sheet 48 over the face of the rear wall 1 as shown in Fig. 1.

By having the apron 21 extend below the water level in the receptacle 5 the air is prevented from passing through the lower part of the water curtain flowing down the apron 21 and is wholly forced upwardly through the opening 31 between the wall portion or apron 20 and the upper portion of the apron 21 and through the sheet 42. Also by having the apron inclined as shown a greater area of space is provided between the lower end portions of the aprons 21 and 12 so that there is a slowing down of the air movement before it makes its turn to pass beneath the lower end of the apron 12 and into the washing chamber 17. The air passage from the work locus which is forward of the apron 21 to the wash chamber 17, as shown in Fig. 1 includes the opening or port 31, the chamber 32, the chamber 33, and the passage 15.

Whatever part of the spray, from the spray gun used in the work locus forwardly of the apron 21, that may strike the water curtain flowing down over the forward face of the apron 21, which spray usually comprises heavy particles of pigments or the like, will be carried down by the water curtain into the receptacle at the front side of the apron 21, and such heavy pigments or the like do not come into contact with any of the sheets of water projected across the passage of the air stream at any locus in the device. Thus such pigments remain at the front side of the apron 21. To prevent the pigments or like particles reaching the rear portion of the receptacle or tank 5, where it is usual to connect the intake to the water circulating pump for the distributing ducts 28 and 28a, it is preferable to provide a barrier or wall 48 extending between the side or end walls 3 and having its upper edge 49 below the normal level 50 of the water 14 in the tank 5, such edge 49 also being at a higher level than the lower edge 51 of the apron 21 or of its lower segment 22, and spaced rearwardly from the apron segment 22 so as to afford a free passage of the clear liquid or water over the edge 49 of the barrier 48 in maintaining the water level 50 in the tank 5. By such means the pigments or similar material particles are held in the forward end of the water tank 5.

From tests we have made we have found that the greater portion of the volume of material, from at least 75%, to 99%, depending on the kind of spray material used, in the material laden air stream, is carried to and down the front of the apron 21 and in the forward portion of the receptacle 5. Only the finer or residual particles are carried up and over the apron 21 to be washed out by the successive water sheets projected across the path of the air stream.

Thus, in the device as shown in Fig. 1, the air receives multiple washings or cleanings by passing through at least five sheets of washing liquid, that is, successively through sheets 42, 38, 39, 15, and 48 and 41. The wet air then passes through the eliminator where the moisture is extracted from the air so that the air passing through the fan 8 is substantially dry.

Referring to Figs. 4 and 5, the distributing duct 28 is shown as located above the distributor plates 34a and 34b with the convex side of the plate 34a opposed to the duct 28 and the concave side of the

plate 34b opposed to the duct 28, so as to project forward sheets 52 and 53 of water toward and to the inclined wall portion 29 toward producing the sheet 31 and the curtain 43 on the apron 21, and rearward sheets 54 and 55 of water toward and to the upper portion of the rear apron 12 toward producing the downward flowing sheet or curtain 48 on the apron 12. The upper part of the duct 28 is provided with a series of openings or slots for the upward projection of water 56 into sheet form toward and against the upper portion of the wall 18 to impinge thereagainst with sufficient force to spread out into water sheets 57 and 58 which run along the surfaces 15 of the wall portion 16 and 4 and to resultantly unite with the water sheets or curtains 43 and 48 flowing down over the aprons 21 and 12. In this way the adhering of the particles to the wall portion 18 is prevented, and the wall portion 18 is maintained clean.

The same effect may be produced by the provision, as shown in Figs. 6 and 7, of auxiliary ducts 59 provided with series of openings or slots for the projection of water sheets 60 and 61 along the surfaces of the wall portions 16 and 4 to resultantly unite with the water forming the water curtains 43 and 48 over the aprons 12 and 21. In Fig. 7 are shown distributor plates 34c and 34d above and below the distributor duct 28 with the convex sides of the plates 34c and 34d opposed to the duct 28, and the duct 28 having upper and lower openings for the projection against and distribution along and over the surfaces of the plates 34c and 34d of water sheets 62 and 63 projected forwardly to and against the wall 4 and water sheets 64 and 65 projected rearwardly to and against the rear portion of the wall 18 and the upper portion of the apron 12, providing for the resultant formation of the water curtains 43 and 48. Because of the divergent projection of the water sheets 62 and 63 against the wall 4 it is preferable to provide the latter with an extension 4a whereby the wall part 28 may be lower and yet afford ample width for the opening 31 between the lower edge of the wall part 28 and the upper portion of the front apron 21.

Fig. 8 shows the duct 28a in the washing chamber 17 and having in addition a distributor plate 66 beneath the duct 28a and openings in its lower wall for projecting water against the plate 66 which distributes it into water sheets 67 and 68 respectively projected forwardly and rearwardly against the walls 12 and 4 to resultantly blend with the water sheets 47 and 48. This means provides for sheets of water 67 and 68 spacedly relative to the sheets of water 48 and 41 for increasing the washing effect.

Thus, when regarding Figs. 4 to 8 inclusive, it will be apparent that the passing of the air stream from the space forwardly of the apron 21 to the eliminator 18 will cause the air to receive from six to eight washings from the several water sheets through which the air stream passes. At the same time all surfaces which might otherwise receive particles of suspended matter will be constantly washed and maintained clean.

While we have herein described and upon the drawings shown an illustrative embodiment of the invention, it is to be understood that the invention is not limited thereto but comprehends other constructions, details, arrangement of parts, features, process steps and the like without departing from the spirit of the invention.

Having thus disclosed the invention, we claim:

1. In a spray booth type of gas cleaner having

a work locus, a wash chamber, an air passage extending from said locus to said chamber, and a liquid receptacle in the lower part of said locus; said passage comprising an apron located in an upright position and rearwardly of said locus, a frontal wall provided spacedly forwardly of the upper portion of said apron and having a depending liquid sheet forming apron inclined rearwardly and downwardly toward said upright apron with its lower edge spaced forwardly of said upright apron to provide an opening for the upward flow of air through said opening forwardly of said upper portion of said upright apron, and means at the upper end of said upright apron for projecting a sheet of liquid to said inclined portion for forming on the latter another sheet of water to flow over said inclined portion and across said opening to said upright apron, a second upright apron located spacedly rearwardly of said first mentioned apron and having its lower end spacedly above said receptacle to provide an opening for passage of air therethrough, said liquid sheet projecting means having means for projecting a sheet of liquid rearwardly to the upper portion of said second apron to form a curtain of liquid flowing down over the front face of said second apron and to form a curtain flowing down from the lower end of said second apron into said receptacle.

2. In a spray booth type of gas cleaner having a work locus, a wash chamber, an air passage extending from said locus to said chamber, and a liquid receptacle in the lower part of said locus; said passage comprising an apron located in an upright position and rearwardly of said locus, a frontal wall provided spacedly forwardly of the upper portion of said apron and having a depending liquid sheet forming apron inclined rearwardly and downwardly toward said upright apron with its lower edge spaced forwardly of said upright apron to provide an opening for the upward flow of air through said opening forwardly of said upper portion of said upright apron, and means at the upper end of said upright apron for projecting a sheet of liquid to said inclined portion for forming on the latter another sheet of water to flow over said inclined portion and across said opening to said upright apron, a second upright apron located spacedly rearwardly of said first mentioned apron and having its lower end spacedly above said receptacle to provide an opening for passage of air therethrough, said liquid sheet projecting means having means for projecting a sheet of liquid rearwardly to the upper portion of said second apron to form a curtain of liquid flowing down over the front face of said second apron and to form a curtain flowing down from the lower end of said second apron into said receptacle, the upper portion of said second apron having an extension extending upwardly and forwardly to said frontal wall to form an upper chamber for reverse flow of the air therethrough whereby the air flows downwardly between the upper portions of said first and second aprons.

3. In a spray booth type of gas cleaner having a work locus, a wash chamber, an air passage extending from said locus to said chamber, and a liquid receptacle in the lower part of said locus; said passage comprising an apron located in an upright position and rearwardly of said locus, a frontal wall provided spacedly forwardly of the upper portion of said apron and having a depending liquid sheet forming apron inclined rearward-

ly and downwardly toward said upright apron with its lower edge spaced forwardly of said upright apron to provide an opening for the upward flow of air through said opening forwardly of said upper portion of said upright apron, and means at the upper end of said upright apron for projecting a sheet of liquid to said inclined portion for forming on the latter another sheet of water to flow over said inclined portion and across said opening to said upright apron, a second upright apron located spacedly rearwardly of said first mentioned apron and having its lower end spacedly above said receptacle to provide an opening for passage of air therethrough, said liquid sheet projecting means having means for projecting a sheet of liquid rearwardly to the upper portion of said second apron to form a curtain of liquid flowing down over the front face of said second apron and to form a curtain flowing down from the lower end of said second apron into said receptacle, a wash chamber located at the rear of said second chamber and communicating with the space forwardly of said second apron by way of the opening beneath the lower end of said second apron, and means in said wash chamber for projecting a sheet of liquid transversely thereof to wash the air flowing upwardly through said chamber.

4. In a spray booth type of gas cleaner having a work locus, a wash chamber, an air passage extending from said locus to said chamber, and a liquid receptacle in the lower part of said locus; said passage comprising an apron located in an upright position and rearwardly of said locus, a frontal wall provided spacedly forwardly of the upper portion of said apron and having a depending liquid sheet forming apron inclined rearwardly and downwardly toward said upright apron with its lower edge spaced forwardly of said upright apron to provide an opening for the upward flow of air through said opening forwardly of said upper portion of said upright apron, and means at the upper end of said upright apron for projecting a sheet of liquid to said inclined portion for forming on the latter another sheet of water to flow over said inclined portion and across said opening to said upright apron, a second upright apron located spacedly rearwardly of said first mentioned apron and having its lower end spacedly above said receptacle to provide an opening for passage of air therethrough, said liquid sheet projecting means having means for projecting a sheet of liquid rearwardly to the upper portion of said second apron to form a curtain of liquid flowing down over the front face of said second apron and to form a curtain flowing down from the lower end of said second apron into said receptacle, a wash chamber located at the rear of said second chamber and communicating with the space forwardly of said second apron by way of the opening beneath the lower end of said second apron, and means in said wash chamber for projecting a sheet of liquid transversely thereof to wash the air flowing upwardly through said chamber, each of said liquid sheet projecting means comprising a duct having a series of apertures in the upper portion thereof for projecting liquid streams upwardly therethrough, and a deflector member spacedly located above said apertures to deflect said liquid streams into sheet form.

5. In a spray booth type of gas cleaner having a work locus, a wash chamber, an air passage extending from said locus to said chamber, and a liquid receptacle in the lower part of said locus;

said passage comprising an apron located in an upright position and rearwardly of said locus, a frontal wall provided spacedly forwardly of the upper portion of said apron and having a depending liquid sheet forming apron inclined rearwardly and downwardly toward said upright apron with its lower edge spaced forwardly of said upright apron to provide an opening for the upward flow of air through said opening forwardly of said upper portion of said upright apron, and means at the upper end of said upright apron for projecting a sheet of liquid to said inclined portion for forming on the latter another sheet of water to flow over said inclined portion and across said opening to said upright apron, a second upright apron located spacedly rearwardly of said first mentioned apron and having its lower end spacedly above said receptacle to provide an opening for passage of air therethrough, said liquid sheet projecting means having means for projecting a sheet of liquid rearwardly to the upper portion of said second apron to form a curtain of liquid flowing down over the front face of said second apron and to form a curtain flowing down from the lower end of said second apron into said receptacle, a wash chamber located at the rear of said second chamber and communicating with the space forwardly of said second apron by way of the opening beneath the lower end of said second apron, and means in said wash chamber for projecting a sheet of liquid transversely thereof to wash the air flowing upwardly through said chamber, each of said liquid sheet projecting means comprising a duct having a series of apertures in the upper portion thereof for projecting liquid streams upwardly therethrough, and a deflector member spacedly located above said apertures to deflect said liquid streams into sheet form, said deflector being curved in cross section with the concaved side thereof opposite said apertures.

6. In a spray booth type of gas cleaner having a work locus, a wash chamber, an air passage extending from said locus to said chamber, and a liquid receptacle in the lower part of said locus; said passage comprising an apron located in an upright position and rearwardly of said locus, a frontal wall provided spacedly forwardly of the upper portion of said apron and having a depending liquid sheet forming apron inclined rearwardly and downwardly toward said upright apron with its lower edge spaced forwardly of said upright apron to provide an opening for the upward flow of air through said opening forwardly of said upper portion of said upright apron, and means at the upper end of said upright apron for projecting a sheet of liquid to said inclined portion for forming on the latter another sheet of water to flow over said inclined portion and across said opening to said upright apron, a second upright apron located spacedly rearwardly of said first mentioned apron and having its lower end spacedly above said receptacle

5 to provide an opening for passage of air therethrough, said liquid sheet projecting means having means for projecting a sheet of liquid rearwardly to the upper portion of said second apron to form a curtain of liquid flowing down over the front face of said second apron and to form a curtain flowing down from the lower end of said second apron into said receptacle, the upper portion of said second apron having an extension extending upwardly and forwardly to said frontal wall to form an upper chamber for reverse flow of the air therethrough whereby the air flows downwardly between the upper portions of said first and second aprons, and means in said upper chamber for projecting a sheet of liquid against said extension for distributing the liquid in a sheet over the surface of said upper chamber to maintain said surface clean.

20 7. In a spray booth type of gas cleaner having a work locus, a wash chamber, an air passage extending from said locus to said chamber, and a liquid receptacle in the lower part of said locus; said passage comprising an apron located in an upright position and rearwardly of said locus, a frontal wall provided spacedly forwardly of the upper portion of said apron and having a depending liquid sheet forming apron inclined rearwardly and downwardly toward said upright apron with its lower edge spaced forwardly of said upright apron to provide an opening for the upward flow of air through said opening forwardly of said upper portion of said upright apron, and means at the upper end of said upright apron for projecting a sheet of liquid to said inclined portion for forming on the latter another sheet of water to flow over said inclined portion and across said opening to said upright apron, a second upright apron located spacedly rearwardly of said first mentioned apron and having its lower end spacedly above said receptacle to provide an opening for passage of air therethrough, said liquid sheet projecting means having means for projecting a sheet of liquid rearwardly to the upper portion of said second apron to form a curtain of liquid flowing down over the front face of said second apron and to form a curtain flowing down from the lower end of said second apron into said receptacle, the upper portion of said second apron having an extension extending upwardly and forwardly to said frontal wall to form an upper chamber for reverse flow of the air therethrough whereby the air flows downwardly between the upper portions of said first and second aprons, said sheet projecting means at the upper end of said upright apron being provided with means for projecting a sheet of liquid against said extension for distributing the liquid in a sheet over the surface of said upper chamber to maintain said surface clean.
